SIPHONING CONTAINER FOR LIQUIDS

Edward Choate, 1416 N. Havenhurst Drive, Los Angeles,
Calif., and Harry W. Hahn, 1700 Glenco Way, Glen-
dale, Calif.

Filed June 10, 1963, Ser. No. 75,284

Term of patent 14 years

(Cl. D58—17)

Fig. 1.

Fig. 2.

Fig. 3.

FIG. 1 is a side elevational view of a siphoning container for liquids, showing our new design;

FIG. 2 is a top plan view thereof; and

FIG. 3 is a bottom plan view thereof.

We claim:

The ornamental design for a siphoning container for liquids, substantially as shown.
